UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

STOP MOTION FOR TWISTERS.

Application filed May 9, 1927. Serial No. 189,761.

This invention relates to improvements in stop motions for a twister of the type in which a pivotally mounted guide is supported by the running yarn and is provided with a tongue which, when the yarn fails, is permitted to feed in between the rolls and thus stop the rotation of the top roll. Devices of this type have been so constructed that considerable difficulty is experienced in removing the tongue when it becomes worn.

One of the objects of the invention is to provide means for supporting the tongue upon the guide in such a manner that the tongue can readily be removed and replaced so that by having a number of tongues on hand, no substantial time will be lost in such removal and replacement.

A further object of the invention is to provide a device of this character which can be more economically constructed and which can be readily applied to any usual type of twister.

In devices of this type it is desirable that the tongue be permitted a limited swinging movement to permit it readily to adjust itself to the bite of the rolls so that it will be fed in surely and accurately therebetween to stop the rotation of the top roll.

These and other objects and features will more fully appear from the following description in the accompanying drawings and will be particularly pointed out in the claims.

The drawings illustrate a simple and preferred form of the invention, together with so much of an ordinary type of twister frame as is necessary to disclose the invention.

In the drawings:

Fig. 1 is a view in vertical cross section through a portion of the twister frame taken adjacent to one of the supports of one of the top rolls and showing the stop motion device with the yarn in running position.

Fig. 2 is a similar view showing the stop motion device in the position it assumes when the yarn fails.

Fig. 3 is a view in front elevation of the upper portion of the construction illustrated in Fig. 1.

Fig. 4 is a top plan view of a portion of the device shown in previous figures.

Fig. 5 is a perspective view of a preferred form of tongue provided with a head adapted to be detachably secured to the guide.

In the twister frame illustrated herein, a series of supports 1 which extend upwardly from the frame 2 present bearings in which is journalled the positively driven bottom roll 3. Bars 4 which are mounted in these supports in the usual manner are provided with upwardly projecting supporting brackets 5 having vertically slotted bearings 6 in which are mounted the journals 7 of the top rolls 8. The top rolls are thereby permitted to rest upon and to be driven by the bottom roll and also to be lifted out of contact with the bottom roll and arrested by the stop motion hereinafter to be described.

The yarn 9 feeds down around the top roll, in between the top and bottom rolls, around the back of the bottom roll, and thence downward through the guide eye 10 which is supported from the finger board 11 projecting at the front of the frame 2.

A preferred form of stop motion device is provided for each top roll or run of yarn. A bracket 12 is secured by means of a bolt or set screw 13 to the front face of one of the top roll supports 5. This bracket is provided with an upwardly extending ear 14 provided with an aperture forming a bearing extending in parallelism with the axis of the top roll.

The guide 15, which preferably but not necessarily is a cylindrical wire of suitable gauge, has a laterally extending cylindrical upper end which is pivotally journalled in this bearing. The bracket 12 desirably is provided with a lug presenting an inclined face 16 which will limit the downward movement of the guide 15 and thereby prevent the roll separating tongue from being drawn too far into the bite of the rolls. The lower free end of the guide 15 has means such as an eye or pig-tail 17 for engaging the running yarn in such a manner that the guide will be supported thereby during the normal running of the yarn, but will be permitted to drop upon the failure of the yarn by breakage or by reason of undue slackness.

The guide 15 is provided with an intermediate open loop which desirably is U-shaped and the legs of which extend in parallelism with the axes of the rolls. This loop is de-

sirably in a substantially horizontal position during the operation of the twister, as illustrated in Fig. 1.

In the present invention the tongue is provided with a head which may be readily assembled upon or removed from this loop portion of the guide. In the preferred construction illustrated herein, the tongue 18 which desirably is of thin sheet metal is secured to a head 19 which may be of cast or forged metal and which is provided with oppositely disposed longitudinally extending grooves 20 and 21 adapted partially to embrace the legs of the loop when the head 18 is inserted therebetween. By reason of this construction, the head of the tongue may be slidably inserted in the open end of the loop. The guide may be made of material of sufficient resilience to retain the head of the tongue within the loop. Desirably, however, means are provided for preventing possible displacement of the head from the loop either lengthwise or by the separation of the legs thereof. Any such means may be employed. A convenient and relatively simple means which is illustrated herein comprises a clip 22, the edges of which are curved downwardly in the same direction to hook over and embrace the legs of the loop, as illustrated particularly in Figs. 1, 2 and 4. This clip desirably is located adjacent to the open end of the loop. When it is desired to remove and replace a yarn tongue, the legs at the open end of the loop may be braced together sufficiently to permit the removal of the clip, whereupon the head of the tongue may be slid lengthwise through the open end of the loop and removed. The head of a new tongue can thereupon be inserted through the open end of the loop and the clip 22 again applied. Such removal and replacement can be done without material wastage of time in the operation of the machine.

In order to give sufficient freedom of movement to permit the tongue readily to engage the bite of the rolls, the grooves 20, 21 in the head may be made of such larger diameter than that of the legs of the loop as will permit the desired amount of lost motion.

It will be readily understood that different forms of head adapted to be removably applied to and removed from the loop may be employed instead of the one illustrated herein, and that various other changes in form, construction and arrangement of parts may be made within the spirit and scope of the invention.

Having thus described the invention, what is claimed as new, and desired to be secured by Letters Patent, is:

1. In a stop motion for twisters having top and bottom rolls and stands therefor, a guide pivotally mounted upon the top roll

stand and normally supported at its lower end by the running yarn and having an intermediate open loop presenting narrowly spaced legs extending in parallelism with the axes of the rolls and a tongue having a head detachably mounted upon the legs of said loop and presenting a free end and adapted to enter between said rolls upon failure of the yarn to support said guide.

2. In a stop motion for twisters having top and bottom rolls and stands therefor, a guide pivotally mounted upon the top roll stand and normally supported at its lower end by the running yarn and having an intermediate open loop presenting narrowly spaced legs extending in parallelism with the axes of the rolls and a tongue having a head provided with means slidable to engage the legs of said loop and to be detachably retained thereby and presenting a free end adapted to enter between said rolls upon failure of the yarn to support said guide.

3. In a stop motion for twisters having top and bottom rolls and stands therefor, a guide pivotally mounted upon the top roll stand and normally supported at its lower end by the running yarn and having an intermediate open loop presenting narrowly spaced legs extending in parallelism with the axes of the rolls and a tongue having a head provided with oppositely disposed longitudinally extending grooves to engage the legs of said loop and adapted to be slidably inserted therebetween and releasable means for retaining said head in said loop.

4. In a stop motion for twisters having top and bottom rolls and stands therefor, a guide pivotally mounted upon the top roll stand and normally supported at its lower end by the running yarn and having an intermediate open loop presenting narrowly spaced legs extending in parallelism with the axes of the rolls and a tongue having a head provided with oppositely disposed longitudinally extending grooves to engage the legs of said loop and adapted to be slidably inserted therebetween and a clip detachably embracing the legs of the loop at the open end thereof.

5. In a stop motion for twisters having top and bottom rolls and stands therefor, a guide pivotally mounted upon the top roll stand and normally supported at its lower end by the running yarn and having an intermediate open loop presenting narrowly spaced legs extending in parallelism with the axes of the rolls, a tongue of thin metal having one end secured to a block provided with oppositely disposed, longitudinally extending grooves to engage the edges of the legs of the loop and adapted to be slidably inserted therebetween and a sheet metal clip embracing the legs of said loop adjacent the open end thereof acting to prevent expansion.

of said loop and to retain the head of the tongue therebetween.

6. In a stop motion for a twister having top and bottom rolls and stands therefor, a guide wire pivotally mounted upon the top roll stand and supported at its lower end by the running yarn and having an intermediate U-shaped loop presenting narrowly spaced legs extending in parallelism with the axes of the rolls, a sheet metal roll-separating tongue having a head comprising a block provided with longitudinal grooves of greater diameter than the diameter of the legs of the loop slidably inserted between the said legs with the grooves thereof engaging said legs adapted to permit limited swinging movement of said tongue whereby the free end thereof will properly enter between the

rolls upon the failure of the yarn to support the said guide and means for retaining said head in said loop. 20

7. A stop motion for twisters comprising a single wire guide having one end bent laterally to provide a journal adapted to be pivotally mounted upon the top roll stand of the twister and having means at its lower end to engage the running yarn and an intermediate laterally extending U-shaped loop, a roll-separating tongue having a head provided with longitudinally extending grooves 30 slidably engaging the legs of said loop and means for preventing separation of the legs of the loop.

In testimony whereof, I have signed my name to this specification.

HARRY A. DAVIS.
